UNITED STATES PATENT OFFICE

2,619,081

STONE SAWING APPARATUS

William D. Johnson, Austin, Tex.

Application April 25, 1952, Serial No. 284,411

7 Claims. (Cl. 125—14)

1

This invention relates to stone sawing apparatus and more particularly to apparatus for sawing stone slabs into brick shaped, rectangular blocks known to the trade as "Romanstone."

It is among the objects of the invention to provide an improved apparatus or mechanism which will receive stone slabs of a predetermined thickness and in one continuous operation, reduce the slabs to brick shaped rectangular blocks known to the trade as "Romanstone"; which performs the successive sawing steps on a slab while the slab is supported on and moved along a continuous supporting table; which receives the stone at one end and discharges the cut blocks at the other end of the table; which operates automatically under manual control; and which is simple and durable in construction, economical to manufacture, easy to use, and effective and efficient in operation.

Other objects and advantages will become apparent from a consideration of the following description and appended claims in conjunction with the accompanying drawings wherein:

Figure 1 is a top plan view of a stone sawing apparatus illustrative of the invention;

Figure 2 is a side elevational view of the apparatus illustrated in Figure 1;

Figure 3 is a fragmentary cross sectional view on an enlarged scale taken on line 3—3 of Figure 1;

Figure 4 is a fragmentary cross sectional view on an enlarged scale taken on the line 4—4 of Figure 1;

Figure 5 is a cross sectional view on the line 5—5 of Figure 4;

Figure 6 is a fragmentary cross sectional view on an enlarged scale on the line 6—6 of Figure 5;

Figure 7 is a fragmentary cross sectional view on the line 7—7 of Figure 1;

Figure 8 is a fragmentary cross sectional view on the line 8—8 of Figure 7;

Figure 9 is a fragmentary cross sectional view on the line 9—9 of Figure 8;

Figure 10 is a fragmentary top plan view of a modified form of apparatus;

Figure 11 is a fragmentary cross sectional view on an enlarged scale on the line 11—11 of Figure 10;

Figure 12 is a fragmentary cross sectional view on the line 12—12 of Figure 11; and

Figure 13 is a fragmentary cross sectional view on an enlarged scale on the line 13—13 of Figure 10.

With continued reference to the drawings, the apparatus comprises a table, generally indicated

2

at 10, and including elongated side members 11 and 12 disposed in spaced apart and substantially parallel relationship and end members 13 and 14 disposed between and connected at their ends to the side members one at each end of the table.

A first saw assembly including a plurality of spaced saws rotatable about a common axis is positioned with respect to the table 10 so that the saws are spaced above the table with the axis extending longitudinally of the table. Supporting columns 15 and 16 are disposed one at each side of the table intermediate the length of the latter and similar columns 17 and 18 are disposed one at each side of the table and spaced

from the columns 15 and 16 respectively. The first saw assembly is mounted on the respective supporting columns for transverse back and forth movement with respect to the table 10. Specifically, spaced apart and substantially parallel rods 19 and 20 extend between the supporting columns 15 and 16 and are secured at their ends to these columns at the upper ends of the latter to provide a guideway extending transversely of the table substantially perpendicular

to the longitudinal center line of and disposed above the table. Similar rods 21 and 22 extend between the columns 17 and 18 and are secured at their ends to these columns at the upper ends of the latter to provide a second guideway 24

spaced from and substantially parallel to the first guideway 23 and extending transversely above the table 10 substantially perpendicular to the longitudinal center line of the latter.

Slide blocks 25 and 26 are mounted on the guideways 23 and 24 respectively and a first saw arbor or horizontal axis 27 is journaled near its opposite ends in bearing blocks 28 and 29 depending from the slide blocks 25 and 26 respectively, the saw arbor 27 extending longitudinally

of the table and being spaced above the table and substantially parallel thereto. Stone cutting saws 30 are mounted on the saw arbor 27 at spaced apart locations therealong for movement transversely of the table between the guideways

23 and 24. In one operative installation the saws 30 are spaced apart approximately 15½ inches.

An electric motor 31 is mounted on the slide block 25 and carries a chain sprocket 32 on one end of its shaft 33. A chain sprocket 34 is mounted on the saw arbor 27 near the corresponding end of the latter and a chain 35 extending around the sprockets 32 and 34 drivingly connects the motor 31 to the saw arbor 27.

A yoke 36 is pivotally connected at its ends to the slide blocks 25 and 26 respectively and a

55

tongue 37 is pivotally connected at one end to the yoke 36 at the center of the latter. The tongue 37 projects substantially perpendicularly from the side member 11 of the table and extends slidably into one end of a cylinder 38 mounted at its ends on fixed supports 39 and 40 spaced outwardly from the table 10. A piston, not illustrated, is mounted on the end of the tongue 37 disposed within the cylinder 38 and fluid pressure conduits 41 and 42 are connected to the cylinder 38 one at each end of the latter for moving the piston back and forth in the cylinder and consequently moving the slide blocks 25 and 26, motor 31, saw arbor 27 and saws 30 back and forth transversely of the table.

The conduits 41 and 42 lead through a suitable manually operated valve from a source of fluid under pressure so that the movement of the saws 30 transversely of the table is subjected to manual control.

A second saw assembly including a plurality of spaced saws rotatable about a common axis positioned in longitudinal spaced relation with respect to the first saw assembly with its saws spaced above the table 10 and its axis extending transversely of the table. Supporting posts 43 and 44 are disposed one at each side of the table at locations spaced from the supporting posts 15 and 16 respectively in a direction away from the posts 15 and 16 and on such posts 43 and 44 is fixedly mounted the second saw assembly. Specifically, bearing blocks or pillows 45 and 46 are mounted on the upper ends of the posts 43 and 44 respectively. A second saw arbor or horizontal axis 47 is journaled near its opposite ends in the bearing blocks 45 and 46 and extends transversely of the table 10 above the table and substantially parallel to the guideways 23 and 24. Stone saws 50 are mounted on the arbor 47 at spaced apart locations therealong, the spacing of these saws in the operative installation referred to above being approximately one and three-quarters inches.

An electric motor 51 is mounted on a supporting post 43 and a chain sprocket 52 is mounted on one end of the motor shaft 53. A chain sprocket 54 is mounted on the saw arbor 47 at the corresponding end of the latter and a chain 55 extending around the sprockets 52 and 54 drivingly connects the motor 51 to the saw arbor 47.

A first conveyor or plurality of rollers 56 extend between the table side members 11 and 12 from the end of the table at the side of the slideways 23 and 24 remote from the saw arbor 47 to a location substantially directly under the rod 22 of the slideway 24 nearest the second saw arbor 47.

As is particularly illustrated in Figures 4, 5 and 6, each of these rollers is provided with an axle 57 projecting at its ends from the respectively opposite ends of the corresponding roller and journaled at its ends in suitable bearings 58 and 59 carried by the side members 11 and 12 of the table and each roller is provided with a cover 60 in the form of a cylindrical body of resilient material, such as rubber. Chain sprockets 61 are mounted one on each roller shaft 57 at the ends of the roller shafts adjacent the side member 11 and a chain 62 extends around the chain sprockets on the end rollers and engage all of the other sprockets to cause all of the rollers to rotate simultaneously in the same direction and at the same speed.

An additional chain sprocket 63 is mounted on

the end of the shaft of the end roller 56 adjacent the side member 11 and an electric motor 64 is mounted on the adjacent supporting post 17. A sleeve 65 is rotatably mounted on the shaft 66 of the motor 64 and a chain sprocket 67 is mounted on the sleeve 65. A chain 68 extends around the sprockets 67 and 63 and drivingly connects the sleeve 65 to the end roller 56 and a manually operated clutch 69 is connected between the motor shaft 66 and the sleeve 65 to provide a manually operated power connection between the motor 65 and the rollers 56.

When the clutch is engaged and the motor 64 in operation, the rollers 56 are all driven in a direction to move a stone slab disposed thereon in a direction from the end of the table at the side of the slideways 23 and 24 remote from the second saw arbor 47 toward the slideways, such a stone slab being illustrated in Figure 1 and generally designated at 70.

A second conveyor is arranged in end-to-end relation with respect to the first conveyor and is mounted on the table 10 for cooperation with the first conveyor. The second conveyor comprises a shaft 71 which extends between the table side members 11 and 12 adjacent and substantially parallel to the roller 56 and this shaft has spaced apart chain sprockets 72 thereon. A similar shaft 73 extends between the side members 11 and 12 at a location spaced from the side of the saw arbor 47 remote from the end roller 56 and has spaced apart chain sprockets thereon corresponding to the sprockets 72. Silent link chains 74 extend around corresponding sprockets on the shafts 71 and 73 and each of these chains passes through the space between two adjacent saws 50, as is particularly illustrated in Figure 8. It is to be noted that the first and second conveyors constitute a conveying means for the support and transport of a stone slab to be cut.

A gear 75 is mounted on the end of the shaft 63 adjacent the support post 43 and a gear 76 is mounted on a stub shaft 77 projecting outwardly from the frame side member 11 adjacent the shaft 73 and meshes with the gear 75. A chain sprocket 78 is mounted on the stub shaft 77 outwardly of the gear 76 and a chain sprocket 79 is mounted on the second saw arbor 47 adjacent the bearing block 45. A chain 80 extends around the sprockets 78 and 79 and this chain and the gears 75 and 76 drivingly connect the saw arbor 47 to the chain sprocket arbor or shaft 73 so that the chains 74 are driven in a direction such that their top runs move from the roller 56 toward the saws 50 when the second saw arbor 47 is driven by the motor 51.

A manually movable stop 81 extends transversely of the table at a location substantially directly below the slideway rod 22 and this stop can be raised to a position at which it projects above the rollers 56, as particularly illustrated in Figure 3 to a position at which it is disposed below the top surfaces of these rollers.

In the use of the device, a stone slab of predetermined thickness, for example four inches, is placed on the rollers 56 at a location spaced from the side of the slideway 23 remote from the second saw arbor 47 with the stop 81 raised. The motor 46 is placed in operation and the clutch 69 engaged to drive the rollers until the front end of the stone slab is brought against the stop 81. With the motor 31 then in operation and driving the saws 30, the hydraulic or pneumatic device 38 is operated to move the saws 30

transversely of the table from the side member 12 to the side member 11 thereby cutting the stone slab into a plurality of strips each approximately four inches thick and fifteen and one-half inches wide and of a length equal to the width of the original slab. When the saws 30 have been moved back clear of the slab the stop 81 is lowered and the clutch 69 reengaged to move the cut strips of stone past the slideway 24 and onto the chains 14, the stop being again raised when these strips have passed the stop to engage the front end of the remainder of the slab and the clutch 69 is then disengaged and the hydraulic or pneumatic device again actuated to move the saws 30 transversely of the table to cut the remainder of the slab into strips, this operation being repeated the number of times necessary for the length of slab being cut.

The strip first cut from the front end of the slab will probably be irregular on its front edge and in such case, will be removed from the chain table leading to the saws 50 before it reaches these saws.

With the motor 51 in operation, as the strips severed from the slab by the saws 30 move past the saws 50 they are cut transversely thereof into brick shaped blocks which are now approximately four inches wide, fifteen and one-half inches long and one and three-quarters inches thick. These blocks are discharged from the chain table onto rollers 85 of a discharge table 86 constituting the end portion of the table 10 at the side of the saw arbor 47 remote from the slideways 23 and 24. The stone blocks are removed from the discharge table for stacking in storage piles or removal to construction projects.

In the modified arrangement illustrated in Figures 10 to 13 inclusive the construction is the same as that illustrated in Figures 1 to 9 inclusive and described above except that the feed chains 74 for the saws 50 are omitted and power driven feed rollers 90 are substituted therefor.

The rollers 90 extend transversely of the machine frame between the side rails 11 and 12 and each roller comprises a shaft 91 journaled at its ends in bearings 92 mounted on the side rails 11 and 12, and a sleeve or cover 93 of resilient material, such as vulcanized rubber, coaxially mounted on the shaft and extending between the side rails 11 and 12.

In the arrangement illustrated the bearings 92 are mounted on the outer sides of the side rails and the end portions of the shafts 91 extend through holes in the side rails and into the corresponding bearings.

Chain sprockets 94 are mounted one on each roller shaft 91 at the outer ends of the bearings 92 and an endless chain 95 extends around all of the chain sprockets 94 and constrains all of the rollers 90 to rotate at the same speed and in the same direction. The gear 75 is mounted on the end roller shaft 91a and is driven by the electric motor 51 through the chain sprockets 79 and 78, chain 80 and gear 76, mounted on the stub shaft 77 carrying the chain sprocket 78, and meshing with gear 75.

The rollers 90a, 90b and 90c nearest the saws 50 are provided with circumferential grooves 96a, 96b, and 96c respectively which receive the cutting edges of the saws 50, as is particularly shown in Figure 11. The grooves 96b in the roller 90b directly under the saws are deeper than the grooves 96a and 96c in the rollers 90a and 90c at respectively opposite sides of roller 90b so that the saw teeth fully clear the rollers.

The rollers 90 are contiguously disposed along the machine frame and their operation is substantially the same as that of the chains 14 in supporting the stone slabs and moving the slabs past the saws 50.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims, are, therefore, intended to be embraced therein.

What is claimed:

1. Stone sawing apparatus comprising an elongated table, slideways disposed intermediate the length of said table and extending transversely of the table above the same in spaced apart and substantially parallel relationship to each other, slides mounted one on each slideway, a first saw arbor journaled at its ends on said slides and extending longitudinally of said table, saws mounted on said first saw arbor at spaced apart locations therealong, power means mounted on one of said slides and drivingly connected to said first saw arbor, fluid pressure operated means supported adjacent said table and connected to said slides for moving said saw arbor and said saws back and forth across said table, bearing blocks disposed one at each side of said table at a location spaced from said slideways, a second saw arbor journaled at its ends in said bearing blocks and extending transversely of said table above the same, saws mounted on said second saw arbor at spaced apart locations therealong, power means drivingly connected to said second saw arbor, said table including power operated means for moving stone slabs therealong in a direction from said slideways to said second saw arbor, and releasable stop means carried by said table between said slideways and said second saw arbor for holding stone slabs stationary on said table while being traversed by the saws on said first saw arbor.

2. Stone sawing apparatus comprising an elongated table, slideways disposed intermediate the length of said table and extending transversely of the table above the same in spaced apart and substantially parallel relationship to each other, slides mounted one on each slideway, a first saw arbor journaled at its ends on said slides and extending longitudinally of said table, saws mounted on said first saw arbor at spaced apart locations therealong, power means mounted on one of said slides and drivingly connected to said first saw arbor, fluid pressure operated means supported adjacent said table and connected to said slides for moving said saw arbor and said saws back and forth across said table, bearing blocks disposed one at each side of said table at a location spaced from said slideways, a second saw arbor journaled at its ends in said bearing blocks and extending transversely of said table above the same, saws mounted on said second saw arbor at spaced apart locations therealong, power means drivingly connected to said second saw arbor, said table including power operated means for moving stone slabs therealong in a direction from said slideways to said second saw arbor, and releasable stop means carried by said table between said slideways and said second saw arbor for holding stone slabs stationary on said second saw arbor.

said table while being traversed by the saws on said first saw arbor, said power operated means for moving stone slabs along said table comprising power driven rollers extending from the slideway adjacent said second saw arbor in a direction away from said second saw arbor and power driven chains extending from the slideway adjacent said second saw arbor under the latter.

3. Stone sawing apparatus comprising an elongated table, slideways disposed intermediate the length of said table and extending transversely of the table above the same in spaced apart and substantially parallel relationship to each other, slides mounted one on each slideway, a first saw arbor journaled at its ends on said slides and extending longitudinally of said table, saws mounted on said first saw arbor at spaced apart locations therealong, power means mounted on one of said slides and drivingly connected to said first saw arbor, fluid pressure operated means supported adjacent said table and connected to said slides for moving said saw arbor and said saws back and forth across said table, bearing blocks disposed one at each side of said table at a location spaced from said slideways, a second saw arbor journaled at its ends in said bearing blocks and extending transversely of said table above the same, saws mounted on said second saw arbor at spaced apart locations therealong, power means drivingly connected to said second saw arbor, said table including power operated means for moving stone slabs therealong in a direction from said slideways to said second saw arbor, and releasable stop means carried by said table between said slideways and said second saw arbor for holding stone slabs stationary on said table while being traversed by the saws on said first saw arbor, said power operated means for moving stone slabs along said table comprising power driven rollers extending from the slideway adjacent said second saw arbor in a direction away from said second saw arbor and power driven rollers extending from the slideway adjacent said second saw arbor under the latter.

4. Stone sawing apparatus comprising an elongated table, slideways disposed intermediate the length of said table and extending transversely of the table above the same in spaced apart and substantially parallel relationship to each other, slides mounted one on each slideway, a first saw arbor journaled at its ends on said slides and extending longitudinally of said table, saws mounted on said first saw arbor at spaced apart locations therealong, power means mounted on one of said slides and drivingly connected to said first saw arbor, fluid pressure operated means supported adjacent said table and connected to said slides for moving said saw arbor and said saws back and forth across said table, bearing blocks disposed one at each side of said table at a location spaced from said slideways, a second saw arbor journaled at its ends in said bearing blocks and extending transversely of said table above the same, saws mounted on said second saw arbor at spaced apart locations therealong, power means drivingly connected to said second saw arbor, said table including power operated means for moving stone slabs therealong in a direction from said slideways to said second saw arbor, and releasable stop means carried by said table between said slideways and said second saw arbor for holding stone slabs stationary on said table while being traversed by the saws on said first saw arbor, the saws on said first saw arbor being spaced apart a

greater distance than the saws on said second saw arbor and said saw arbors being individually driven by separate power plants.

5. Stone sawing apparatus comprising an elongated table, slideways disposed intermediate the length of said table and extending transversely of the table above the same in spaced apart and substantially parallel relationship to each other, slides mounted one on each slideway, a first saw arbor journaled at its ends on said slides and extending longitudinally of said table, saws mounted on said first saw arbor at spaced apart locations therealong, power means mounted on one of said slides and drivingly connected to said first saw arbor, fluid pressure operated means supported adjacent said table and connected to said slides for moving said saw arbor and said saws back and forth across said table, bearing blocks disposed one at each side of said table at a location spaced from said slideways, a second saw arbor journaled at its ends in said bearing blocks and extending transversely of said table above the same, saws mounted on said second saw arbor at spaced apart locations therealong, power means drivingly connected to said second saw arbor, said table including power operated means for moving stone slabs therealong in a direction from said slideways to said second saw arbor, and releasable stop means carried by said table between said slideways and said second saw arbor for holding stone slabs stationary on said table while being traversed by the saws on said first saw arbor, said power operated means for moving stone slabs along said table comprising power driven rollers extending from the slideway adjacent said second saw arbor in a direction away from said second saw arbor and power driven chains extending from the slideway adjacent said second saw arbor under the latter, said saw arbors being individually driven by separate power plants and said rollers being driven by a manually controlled power plant separate from the power plants driving said saw arbors.

6. Stone sawing apparatus comprising a horizontally disposed conveying means for the support and transport of a stone slab to be cut, a first saw assembly including a plurality of spaced saws rotatable about a common horizontal axis positioned so that the saws are spaced above said conveying means with said axis extending longitudinally of the latter means, said assembly being mounted for traversed back and forth movement with respect to said conveying means, means operatively connected to said assembly for effecting the traversed back and forth movement of the latter, and a second saw assembly including a plurality of spaced saws rotatable about a common horizontal axis positioned in longitudinal spaced relation with respect to said first assembly with its saws spaced above said conveying means and its axis extending transversely of the latter means, said second assembly being fixedly mounted with respect to said conveying means.

7. Stone sawing apparatus comprising a horizontally disposed conveying means for the support and transport of a stone slab to be cut, said conveying means embodying a first conveyor and a second conveyor arranged in end to end relation with respect to said first conveyor, a first saw assembly including a plurality of spaced saws rotatable about a common horizontal axis positioned so that the saws are spaced above said conveying means with said axis extending longi-

tudinally of the latter means, said assembly being mounted for traversed back and forth movement with respect to said conveying means, means operatively connected to said assembly for effecting the traversed back and forth movement of the latter, a second saw assembly including a plurality of spaced saws rotatable about a common horizontal axis positioned in longitudinal spaced relation with respect to said first assembly with its saws spaced above said conveying means and 10

its axis extending transversely of the latter means, said second assembly being fixedly mounted with respect to said conveying means, and a stop interposed between the facing ends of said first and second conveyors and movable vertically above and below said conveyors for engagement with an end face of the slab to be cut.

WILLIAM D. JOHNSON.
